UNITED STATES PATENT OFFICE.

ARTHUR CHESTER JOHN ALLEN, OF SAN ANTONIO, TEXAS.

GREASE-CUP.

1,358,493.

Specification of Letters Patent.

Patented Nov. 9, 1920.

Application filed January 10, 1920. Serial No. 350,524.

To all whom it may concern:

Be it known that I, ARTHUR CHESTER JOHN ALLEN, of San Antonio, in the county of Bexar and State of Texas, have invented 5 certain new and useful Improvements in Grease-Cups; and I do hereby declare the following to be a full, clear, and exact description of the invention, such as will enable others skilled in the art to which it applies to make and use the same.

My invention relates to the lubrication of machine parts, and the object of the invention is to provide an improved grease cup adapted for this purpose which has a simple 15 and effective means for positively forcing the lubricant through the cup and a complementary tool for actuating the forcing means.

In the accompanying drawings, Figure 1 20 is a view in perspective of a grease cup and complementary tool embodying my invention. Fig. 2 is an elevation with the grease cup and part of the tool shown in longitudinal section. Fig. 3 is an enlarged detail 25 view.

My improved grease cup includes, as shown in the drawings, a barrel 1 having an apertured base 2 adapted to be secured into the casing or support of the part to be 30 lubricated, the other end of the barrel terminating in a hollow stem or sleeve which has a series of hexagonal portions 3, 4 and 5, the portion 4 being arranged eccentrically to the portions 3 and 5. The base 2 is detachably connected with the barrel, the locking means being shown in the form of lateral 35 outwardly projecting spaced apart lugs 6 on the barrel adapted to engage with inwardly extending spaced apart flanges 7 on the base, each of these flanges having a stop 8 which limits the turning movement between the barrel and base. A plunger 9 is fitted 40 grease-tight within the barrel 1 and this plunger has a rod 10 which fits within the 45 sleeve of the barrel. A coiled spring 12 hugging the inner wall of the barrel is positioned between the plunger and the base end of the barrel, and this spring normally maintains the plunger at the sleeve end of 50 the barrel. The latter has an inwardly extending flange 13 which forms a seat for the spring at its base end.

A tool complementary to the grease cup has an elongated handle 20 and a tube 21 55 which is provided with a bore of hexagonal form, indicated at 22, at one end, the

bore of the tube at the other end being preferably circular in form, as at 23. Equally spaced around the sides of the tube are three spring arms 24. Each of these 60 arms is fixedly secured to the tube at one end, its other end having a lug 25 which projects into the tube through an aperture provided for that purpose at a point slightly to one side of the center line of the hexagonal surface through which it extends. A rod 26 paralleling the handle throughout its greater portion extends a slight distance into the tube through the bore 23, a spring 27 coiled about the rod and seated between 70 the tube and stop 28 on the rod normally maintaining the rod in its outermost position. A lever 30 has a pivotal connection with the rod at its outermost end and is fulcrumed on the handle in such position 75 that its free end and the end of the handle afford a hand grip for the manipulation of the rod.

The tube is placed over the hollow stem or sleeve of the grease cup and is forced 80 thereonto. Engagement between the sleeve and the lugs 25 forcing the spring arms outwardly, such arms returning to their normal position when the tube has been forced sufficiently far on to the sleeve to allow the 85 lugs to engage with the surfaces of the portion 4 of such sleeve, the tool being thus locked with the grease cup. The projection of the lugs through the tube at one side of the center line of the hexagonal surface insures 90 a snapping of the lug into engagement with the flat surface of portion 4 immediately adjacent the lug. This insures the positioning of the lug so that an outward pull on the tool will cause the lug to 95 engage the portion 5 at a point where two of its surfaces merge, this angular point thus forming a stop for the lug. In removing the tool it is necessary to give it a slight turn so as to expand the spring arms 100 to bring the lugs into a plane with the surfaces of the portion 5. The extreme end of the tube engages the stem portion 3 and serves as a wrench for turning the barrel 105 relatively to its base so as to detach these parts. When detached the barrel is securely held by the tool. Pressure on the lever 30 will force the rod 26 farther into the tube and bring it in contact with the plunger rod 10, continued pressure serving to force 110 the plunger against the tension of its spring toward the base end of the barrel. With

the plunger forced inwardly the barrel may be placed in a can of grease, release of the lever 30 causing the plunger to quickly return to its normal position under the pressure of its spring, thus sucking the grease into the barrel. With the latter so filled it is attached to its base, and the lever 30 again manipulated to force the tool rod 26 and the plunger rod 10 against the tension 10 of the respective springs 12 and 27, this movement forcing the grease in the barrel through the passageway of its base to the machine part to be lubricated. When a sufficient amount of lubricant has thus been forced home, the barrel may be again filled 15 and the tool immediately detached, leaving the grease cup filled for a later forcible feeding.

I claim as my invention:

20 1. In combination, a grease cup having an apertured detachable base, a spring held plunger, said grease cup having an opening at one end permitting access to said plunger, and a plunger actuating element detachably connected with said grease cup.

25 2. In combination, a grease cup having an apertured detachable base at one end and a sleeve at its opposite end, a spring held plunger within said cup and having a portion extending into said sleeve, and a plunger actuating element adapted to be detachably connected with said grease cup, said plunger actuating element including a spring controlled rod adapted to be projected into said sleeve to actuate said plunger.

30 3. In combination, a grease cup having an apertured detachable base at one end and a sleeve at its opposite end, a spring held plunger within said cup having a portion extending into said sleeve, a tubular member adapted to be detachably connected with said sleeve, a spring controlled rod extending into said tubular member, and 35 means for projecting said rod into said sleeve to actuate said plunger.

4. In combination, a grease cup having an apertured detachable base at one end and a sleeve at its opposite end, a spring held plunger within said cup having a portion 50 extending into said sleeve, a tubular member adapted to be detachably connected with said sleeve, a handle on said member, a spring controlled rod extending into said tubular member, and a lever secured to said rod and fulcrumed on said handle for projecting said rod into said sleeve to actuate said plunger.

5. In combination, a grease cup having an apertured detachable base at one end and a sleeve at its opposite end, the outer surface of said sleeve having a plurality of flat faces, a spring held plunger within said cup and having a portion extending into said sleeve, a tubular member adapted to fit over 60 said sleeve and having a portion of its bore designed to engage the flat faces of said sleeve, means for detachably securing said tubular member to said sleeve, a spring controlled rod extending into said tubular member, and means for projecting said rod into 65 said sleeve to actuate said plunger.

6. In combination, a grease cup having an apertured detachable base at one end and a sleeve at its opposite end, the outer surface of said sleeve having a plurality of flat faces arranged in series eccentric to each other, a spring held plunger within said cup and having a portion extending into said sleeve, a tubular member adapted 70 to fit over said sleeve and having a portion of its bore designed to engage one of the series of flat faces of said sleeve, means for detachably gripping another of the series of flat faces to secure said tubular member to said sleeve, a spring controlled rod extending into said tubular member, and means for projecting said rod into 75 said sleeve to actuate said plunger.

In testimony whereof I have signed this 80 specification.

ARTHUR CHESTER JOHN ALLEN.
